(Cl. D29—28)

To all whom it may concern:

Be it known, that we, William E. Young and Phyllis L. Young, citizens of the United States and residents of Portland, county of Multnomah, and State of Oregon, have invented a new, original, and ornamental Design for a Combined Mantel Ornament and Flower Holder, of which the following is a specification, reference being had to the accompanying drawings, forming a part thereof.

In the drawings:

Fig. 1 is a front elevational view of a combined mantel ornament and flower holder showing our new design;

Fig. 2 is a side elevational view thereof; and

Fig. 3 is a perspective view thereof.

We claim:

The ornamental design for a combined mantel ornament and flower holder, substantially as shown.

WILLIAM E. YOUNG.
PHYLLIS L. YOUNG.
